CLAIM

The ornamental design for a shoe, as shown and described.

DESCRIPTION

FIG. 1 is a side view of a shoe showing our new design; FIG. 2 is a rear perspective view thereof; FIG. 3 is an enlarged view of the region shown in even-length broken lines in FIG. 2 thereof; FIG. 4 is a side view of a shoe showing an alternative embodiment of our new design; FIG. 5 is a rear perspective view thereof; FIG. 6 is an enlarged view of the region shown in even-length broken lines in FIG. 5 thereof; FIG. 7 is a side view of a shoe showing an alternative embodiment of our new design; FIG. 8 is a rear perspective view thereof; FIG. 9 is an enlarged view of the region shown in even-length broken lines in FIG. 8 thereof; FIG. 10 is a side view of a shoe showing an alternative embodiment of our new design; FIG. 11 is a rear perspective view thereof; and, FIG. 12 is an enlarged view of the region shown in even-length broken lines in FIG. 11 thereof. The uneven-length broken lines immediately adjacent to the shaded area define the bounds of the claimed design and form no part thereof. The uneven-length broken lines depicting the remainder of the shoe show features that form no part of the claimed design.

1 Claim, 12 Drawing Sheets
